LIQUID FUEL BURNING SYSTEM AND
REGULATING APPARATUS

Forrest R. Whitcomb, Winchendon, Mass.

Application July 25, 1936, Serial No. 92,613

7 Claims. (Cl. 158—36)

This invention relates to liquid fuel burning systems and apparatus, and to a device responsive to a condition that is apt to be variable as, for instance, the pressure in a steam boiler, for controlling the flow of fuel to the burner in such manner as to maintain the condition, as the steam pressure, substantially constant.

My invention particularly relates, although it is not necessarily restricted, to the so-called vaporizing type of liquid fuel or oil burner and its fuel supply and control system. A vaporizing type of oil burner consists of a burner having small openings through a wall thereof through which a combustible mixture of oil vapor and air flows and burns outside the burner. The liquid oil that is supplied under pressure to the burner is first vaporized by passing it through a vaporizing tube that, usually, is heated by the flame of the burner. The oil vapor is discharged at a substantial velocity through a small orifice into a combining or mixing tube where it entrains sufficient air for combustion; and the mixture is passed into the burner. Heretofore, the regulation of the flame has been accomplished by controlling the flow of oil vapor by a needle valve the point of which projects into the fuel orifice to regulate the effective cross-sectional area thereof.

Vaporizing the oil usually results in the formation of solid carbon particles which flow with the oil vapor to the discharge orifice. Much of the carbon particles are too large to pass through the orifice and hence collect around and in it and thus plug it frequently; and one of the functions of the needle valve is to break away the carbon deposit so that the fuel can pass therethrough although ultimately the end of the needle burns off to such an extent that the needle valve point cannot keep the passage clear. This location of the fuel regulating valve is objectionable since it has to be packed against the rather high pressure and high temperature of the oil vapor and in practice cannot be maintained constantly tight so that oil vapor leaks out and ignites and backfires the burner and necessitates the restarting of the fire.

An object of the present invention is the provision of a vaporizing type of burner and a fuel supply therefor wherein regulation of the fuel supply to the burner is obtained by control of the liquid fuel so that troubles from leaking oil vapor and backfiring are eliminated.

A liquid fuel burner is often associated with a heating apparatus, as a steam boiler, for the purpose of automatically maintaining constant a

predetermined condition as, for instance, a constant steam pressure in the boiler. It is an object of the present invention to provide a novel oil flow regulating system automatically responsive to the predetermined condition, as the steam pressure, or to a predetermined manual setting at will, to control the flow of oil in such manner as to maintain the predetermined condition constant.

In particular it is an object of the invention to provide an improved fuel regulating apparatus so arranged as to provide for a high flow of oil corresponding usually to the maximum capacity of the burner and a low flow of oil corresponding usually to the amount of oil necessary to keep the burner in reliable operation, with means responsive to the predetermined condition as the steam pressure or rate of combustion desired to effect the flow of oil at either high or low volume or any point in between, in accordance with con-

In supplying oil for the low flame operation of the burner the size of the orifice through which the liquid fuel passes is relatively minute, especially for a low maximum capacity burner. Such a small orifice ordinarily cannot be maintained clear of obstruction, notwithstanding that the oil may be filtered as completely as is practicable prior to its passage to the orifice. The usual fuel oils, at least those present in common use, seem to contain solid matter or waxes that cannot be filtered out but which collect at a small orifice where there is a sharp drop in pressure and plug the orifice.

A further object of the present invention is the provision of an oil-regulating apparatus wherein the control valve is so arranged that it is caused to move frequently enough to dislodge any collection of solid matter that may tend to plug the orifice and so keep the orifice clear.

Another object of the invention is an oil supply system having an oil-regulating apparatus that operates to maintain a constant rate of combustion, for any setting thereof, irrespective of a fluctuating oil supply pressure.

A further object of the invention is the provision of an oil regulating valve subject both to the pressure of the oil supply and also to the pressure of the oil vapor, both of which can vary, and so arranged as to maintain a constant oil vapor pressure notwithstanding variations of oil supply pressure and varying conditions, such as varying vaporizing temperatures, that tend toward varying vapor pressures. The valve further is so arranged that it can be adjusted, either

manually or otherwise, for different vapor pressures and to maintain constant the pressure for which it is adjusted.

A further object of the invention is the provision of an oil regulating apparatus so constructed and arranged that it is particularly sensitive to small variations of steam pressure in the boiler heated by the burner and hence is capable of maintaining the steam pressure constant within close limits.

10 A yet further object of the invention is the provision of an oil regulating apparatus having a steam pressure controlled high flame valve that is so balanced or constructed that it is unaffected by variations in the pressure of the oil that it controls.

A further object is generally to improve upon oil burning systems and regulating apparatus therefor.

20 Fig. 1 is a plan view illustrating an oil burning system embodying the present invention associated with a steam boiler.

Fig. 2 is an enlarged sectional detail of the filter in the oil vapor pipe of the system.

25 Fig. 3 is a side elevation of the pressure regulating apparatus forming a part of the present invention.

Fig. 4 is a sectional view taken along line 4—4 of Fig. 3.

30 Fig. 5 is a section along line 5—5 of Fig. 4.

Fig. 6 is a sectional detail of the supporting plate for the high flame valve.

The liquid fuel burning system embodying the present invention is hereby shown associated with the steam boiler 10 having the combustion chamber 12 in which the burner 14 is located. The burner is provided with orifices 16 through which a combustible mixture passes and is burned above the burner, and a combining or mixing tube 18 through which the mixture of oil vapor and air is directed into the burner. Liquid fuel is supplied under regulated pressure through a pipe 20 having a pass 22 that extends through the flame zone or combustion space of the boiler 40 in a position to be sufficiently highly heated to convert the oil therein into a vapor. The vapor passes through the pipe 24 and through a small orifice in a nozzle 26 and discharges into the tube 18 wherein it entrains sufficient air for 45 good combustion.

The flow of the liquid oil is regulated by a flow regulating device 23, the operation of which is controlled by a steam pressure in the boiler 50 through a steam pipe 25. Oil is supplied preferably under pressure to the regulating device through a pipe 26 from an oil pump 28 which draws oil from a suitable supply source. The pump 28 may comprise a single acting pump having a reciprocating piston 30 operated by a solenoid 32 the circuit of which is controlled by a switch 34 so arranged that when the piston is at the bottom of its working stroke the solenoid is energized and raises the piston. The solenoid is de-energized at the top of its suction stroke and 60 the piston returns on a delivering stroke by spring means or the equivalent not shown, the springs supplying the pumping pressure.

The flow regulating apparatus 23 comprises a lower cylindrical casing 36, see especially Figs. 3 and 4, the open lower end of which is closed removably by a plug 38 having a screw-threaded connection with the end of the steam pipe 25. The plug contains a cylindrical recess in its upper face in which the cylindrical lower open

end 40 of an expansible bellows 42 is secured as soldered in a fluid tight manner. The bellows 42 is preferably composed of metal having a plurality of annular corrugations so that it is capable of lengthwise expansion. The upper end 5 of the bellows is closed and a piston 44 bears loosely thereagainst, the piston being cupped at its lower end to receive the upper end of the bellows so that the two are held against relative lateral displacement.

10 The piston 44 is capable of free axial movement within the circular opening of a transverse wall 46 of the casing 36, which wall holds the piston against undue axial displacement, although ordinarily the piston is out of engagement with 15 said wall. The piston is screw-threaded onto the lower end of a piston rod 48 which extends through the upper end of the casing 36. A pressure adjusting plug 50 loosely surrounds the 20 piston rod and is screw-threaded into the upper end wall 52 of the casing 36 and bears against the upper end of a compression spring 54. The lower end of the spring bears against a washer 56 which loosely surrounds the lower end of the piston rod and is seated normally upon the top 25 of the piston 44. Said washer, however, is larger in diameter than said piston and can overlie and bear upon the wall 46 of the casing 36 at times of insufficient steam pressure so as to take the load of the spring from the bellows at such 30 times and prevent undue collapse of the bellows. The pressure adjusting plug 50 is provided with opposed spanner openings 58 by which the plug 35 can be rotated to adjust the compression pressure of the spring on the piston and hence adjust the steam pressure at which the regulating device is maintained to operate.

A valve casing 60 is disposed above the top 40 of the casing 36 and is secured in spaced relation therewith by opposed sets of upper and lower spacing tubes 62 and 64 which are received loosely on upstanding tie rods 66 screw-threaded in ears 68 of the casing 36 and passed loosely through ears 70 of the valve casing 60, the valve casing being clamped against the ends of the upper casing tube 60 by nuts 72 screw-threaded on the upper ends of said tie rods. The valve casing 60 is provided with a liquid fuel inlet passage 74 and a liquid fuel outlet passage 76. Communication between said passages is controlled by a high flame valve member or stem 78 having a cylindrical upper end terminating in a conical valve face 80 and having an enlarged lower end 82. The valve stem 78 is adapted for free vertical reciprocatory movements in a vertical cylindrical stem passage 84 that communicates with the inlet passage 74 through a conduit 86 and with the outlet passage 78 through a conduit 88, the conical end 80 of the valve stem controlling the flow of fluid through the passage 88. The lower end of the valve stem 78 is fixed to the middle of a circular stem-supporting disc 90 having upper and lower annular shoulders 92 and an intermediate outstanding annular flange 94. An upper flexible corrugated metal bellows 96 has its lower open end surrounding and secured in an oil tight manner as soldered to the upper annular shoulder 92 and has its upper open end similarly secured to a cylindrical boss 70 98 of the valve casing 60, thereby surrounding the valve stem. A second lower flexible metal bellows 100 has its upper cylindrical open end surrounding and secured in an oil tight manner to the lower annular shoulder 92 of the disc 75

90 and has a cylindrical projecting closed lower end 102. Said bellows rests upon and its bottom end 102 projects into a recess or opening of a supporting plate 104, the opposite ends of said plate are received on the tie rods 66 and are clamped between the lower and upper spacing tubes 62 and 64. The valve stem 78 is provided with an axially directed oil channel 106 which permits free communication between the high pressure oil inlet 74 and the interior of the upper bellows 96. The valve supporting disc 90 is provided with an oil channel 108 which establishes communication between the two bellows. This arrangement provides a packless valve, that is, one that is permanently oil tight without the use of a packing gland and one wherein the pressure of the inlet oil on the valve stem is balanced so that there is no material tendency for the valve stem to move in either direction due to the oil pressure.

The valve stem 78 is reciprocated by corresponding movements of the piston rod 48. To this end a yoke 110 is fixed to the upper end of the piston rod 48 and has oppositely disposed vertically extended arms 112 which are located on opposite sides of the valve bellows and terminate in vertically adjustable screws 114 having conical upper ends 116 above which extend locating projections 118. A valve supporting plate 120 has ears 122 which rest on or fulcrum upon the conical ends 116 of said screws and has apertures 124 through which the locating projections 118 are loosely extended. This arrangement gives the plate freedom for rocking movement in directions transversely of the line through the screws. The plate is provided with a cup-shaped recess 126, see especially Figs. 4 and 6, in which the valve stem supporting disc 90 is located. The bottom wall 128 of said plate 120 is provided with a pair of diametrically opposed projections or fulcrums 130 angularly displaced 90° from the line of the screws 114 and which fulcrum supports the outstanding flange 92 of said disc 90. Said disc by virtue of these projections and the fulcrum support for the plate 102 is capable of universal pivotal movement with respect to the operating yoke 110, and hence the valve member 78 is free for vertical movement about its own vertical axis irrespective of the alignment of the operating yoke 110. With this arrangement both the operating piston 44 and the valve member 78 are free for movement with a minimum of sidewise restriction since the parts are supported entirely on flexible bellows which are free to expand along their own axis and to tilt sidewise in any direction. The valve is thus capable of responding in a very sensitive manner to a fluctuation of steam pressure.

As has been stated above, the valve member 78 is free from influence by the high pressure oil since the pressure of oil on the upper and lower ends of the valve member is substantially equal, the bellows 96 and 100 being filled with oil at the pressure of the inlet oil. The pressure of oil in the interior of the bellows is supported by the plate 104 so that the bellows remain of constant length regardless of fluctuations of oil pressure. Hence the movement of the valve member under control of the steam actuated bellows 42 is independent of the oil pressure and is governed solely by the steam pressure.

The valve as thus described is adapted to open when the steam pressure is sufficiently low and to close when the steam pressure is sufficiently high. A low flame valve is provided to main-

tain a predetermined minimum flow of oil to the burner at times when the high flame valve 78 is closed. The low flame valve comprises a flexible diaphragm 132 formed of a thin flat metal sheet having a down-turned rim or flange 133 which surrounds an upstanding annular flange 134 of the valve casing 60 and is secured to said flange in an oil tight manner, as by soldering. The shallow oil chamber 136 located under the diaphragm and within said flange communicates with the outlet passage 76 through a small connecting passage 138 and with the inlet passage 74 through a valve passage 140 and an intermediate chamber 142 that is open to the inlet passage 74. An exteriorly and interiorly screw-threaded neck 144 is fixed to and upstands above the diaphragm 130 and a valve carrying and adjusting screw 146 is screw-threaded in said neck. A packing cap 148 is screw-threaded upon said neck and, with the packing material therein, seals said screw against leakage of oil thereabout. The screw 146 has a slender valve rod or stem 150 extended axially therethrough and fixed thereto. Said rod extends through the central opening in the diaphragm 130 and through the valve passage 144 and terminates in a conical valve member 152 disposed in the passage 142 in positions to control the entrance of fuel through said passage 140.

Said valve member 152 by reason of said passage 138 is responsive to pressure conditions in the outlet passage 76 and hence to the pressure of the oil vapor conditions in the vapor generator 22. When the pressure in the outlet passage 76 is relatively high due to the high flame valve 78 being open the pressure acts on the under side of the diaphragm 132 to flex it outwardly thereby moving the low flame valve 152 upwardly and sealing the entrance to the passage 140. When, however, the steam pressure in the boiler reaches a sufficiently high point to cause the high flame valve 78 to close, the pressure in the outlet passage 76 drops due to the discharge of vaporized fuel into the burner. When the pressure is sufficiently low the diaphragm 130 flexes downwardly due to its inherent resiliency and causes the low flame valve member 150 to open thereby to admit the predetermined minimum amount of fuel to pass to the burner. The minimum amount of fuel may be varied within limits by changing the setting of the adjusting screw 146.

The low flame valve maintains a constant pressure of oil vapor at the nozzle 26 for if the pressure tends to rise in the outlet passage 76 the low flame valve closes somewhat; and if the pressure drops the low flame valve opens somewhat. The operation of the low flame valve is such that it is in continual reciprocatory movement in order to maintain a constant pressure condition in the outlet passage. When the valve opens to admit oil the oil is vaporized and builds up a vapor pressure that causes the partial closing of the valve member. The valve member stays in this semi-closed position until the oil has been consumed and the pressure drops whereupon the valve again opens. Such movements of the valve serve to maintain a constant oil vapor pressure. The response of the valve to varying oil supply pressures is similar. Such further movements of the valve are frequent enough and are sufficient in amplitude to dislodge solid particles from around the valve member and hence to keep the passage through the valve free and clear, as has been found by experience.

A filter 154 is located in the oil vapor pipe 24 between the oil vaporizing pipe 22 and the nozzle 26 to prevent the passage of solid matter into the nozzle. The filter, as illustrated in detail in Fig. 2, comprises a gas tight casing 156 having inlet and outlet passages 158 and 160, respectively, between which a filter element 162 is located in such manner that all of the vapor is constrained to pass through the filter element. The filter element comprises a porous disc of ceramic material such as carborundum or the like, molded into shape and having a plurality of pores or small tortuous passages therethrough that are sufficiently small to entrap carbon and other solid particles in the vapor stream and prevent them from passing to the orifice. The combined area of the small pores or passages through the filter element is sufficiently great so that the filter element does not offer any deleterious resistance to the flow of heated vapor even after long periods of use. The use of the filter element not only prevents the orifice in the nozzle 26 from clogging and thereby permits the fuel regulation to be effected from the liquid oil side of the system but also provides a cleaner flame since it entraps the small solid particles that would otherwise pass through the orifice and into the flame to form soot. The filter preferably is located above the burner or where it receives sufficient heat from the flame thereof to prevent it from condensing the oil vapor.

I claim:

1. An oil burning system including an oil burner, oil flow regulating apparatus for said burner comprising high and low flame valves having movable valve members and a common outlet passage connected with said burner, means for operating said high flame valve member to change the oil pressure in said outlet passage, and operating means for said low flame valve member responsive to a predetermined low oil pressure in said outlet passage to maintain said pressure substantially constant and responsive to an elevated pressure to move said low flame valve member into closed position.
2. An oil burning system including an oil burner, oil flow regulating apparatus for said burner comprising high flame and low flame valves having valve members and a common inlet passage and a common outlet connected with said burner, operating means for said low flame valve member responsive to a predetermined low oil pressure in said outlet passage for maintaining said pressure substantially constant, and operating means for said high flame valve member to open and close it to change the pressure of oil in said outlet passage between wide limits and to control the operation of said low flame valve member.
3. An oil burning system including an oil burner, oil flow regulating apparatus for said burner comprising a low flame valve having inlet and outlet passages, said outlet passage being connected to said burner, means responsive to a low oil pressure in said outlet passage for controlling the opening of said valve, and a high flame valve having means for admitting high pressure oil into said outlet passage to effect the closing of said low flame valve.
4. An oil burning system including an oil burner, oil flow regulating apparatus for said burner comprising a valve casing having inlet and outlet passages, said outlet passage being connected with said burner, a movable valve member controlling the flow of oil between said

inlet and outlet passages, a flexible diaphragm at all times responsive to oil pressure in said outlet passage and at the burner, and an adjusting screw carried by said diaphragm and carrying said valve member, said screw being adjustable in the line of operation of said valve member whereby to determine the flow of oil through said valve at predetermined settings of said valve member, a second passage connecting said inlet and outlet passages, and a second valve member in said second passage operative to admit oil into said outlet passage independently of said first valve member and in amount sufficient to act on said diaphragm and close said first valve member and increase the supply of oil to the burner.

5. An oil burning system including a burner, oil flow regulating apparatus for said burner comprising a valve casing having inlet and outlet passages, said outlet passage being connected with said burner, a movable valve member controlling the flow of oil between said passages, a flexible diaphragm at all times responsive to oil vapor pressure at the burner operatively connected with said valve member for varying its position in response to different oil pressures on said diaphragm, and means for adjusting the relative position of said valve member independently of the action of said diaphragm, a second passage connecting said inlet and outlet passages, and a second valve member in said second passage operative to admit oil into said outlet passage independently of said first valve member and in amount sufficient to act on said diaphragm and close said first valve member and increase the supply of oil to the burner.

6. An oil burning system including a burner, oil flow regulating apparatus for said burner including a valve casing having inlet and outlet passages and an annular flange, said outlet passage being connected with said burner, a flexible diaphragm secured to said flange, said casing having a valve passage leading from said inlet passage and opening into the space under said diaphragm and a second passage establishing communication between said space and said outlet passage, said diaphragm being at all times responsive to burner vapor pressure, a valve member in said first passage, and a valve adjusting screw having a screw-threaded connection with said diaphragm and carrying said valve member for adjusting the setting of said valve member to regulate the rate of operation of said burner, a second passage connecting said inlet and outlet passages, and a second valve member in said second passage operative to admit oil into said outlet passage independently of said first valve member and in amount sufficient to act on said diaphragm and close said first valve member and increase the supply of oil to the burner.

7. In an oil burner system having a burner, means providing an orifice for discharging oil vapor into the burner, means for supplying oil under pressure, the combination therewith of valve means for controlling the flow of oil from said supply to said vaporizing means, said valve means having means responsive to pressure of the oil vapor and operative automatically to maintain a constant pressure of oil vapor irrespective of variations of pressure of the oil supply, and means for admitting oil to said vaporizing means independently of said valve means in a quantity sufficient to increase the vapor pressure and effect the closing of said valve means.
